UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,556, dated January 7, 1890.

Application filed December 9, 1889. Serial No. 333,154. Term of patent 3½ years.

To all whom it may concern:

Be it known that I, WILLIAM K. BENEDICT, of the city and county of New York, in the State of New York, have invented and produced a new and original Design for a Residence, of which the following is a specification, reference being had to the drawings forming a part thereof.

Similar letters of reference designate corresponding parts in all the figures.

A residence embodying my design is generally rectangular in shape on the ground plan and has a rearward extension. It comprises a first and second story and an attic story. The second story is substantially L-shaped, and the residence is surmounted by a gable roof. The front of the first story shows an octagonal bay A. At one side of the octagonal bay A is a porch B. This porch has arch-shaped portions a, which spring from pillars b. Above the porch B is a balcony C. The side D of the residence is substantially flat. The second story has at the front an overhanging portion E. Above the bay A consoles e extend between the overhanging portions E and the bay A. The roof comprises two portions F and G, which portions are shown as extending substantially at right angles to each other. The eaves of the roof extend only to the top of the second story. Upon the portion G of the roof is shown a dormer-window H, having a curved roof. The rear extension I is shown as having a hipped roof.

What I claim is—

The design for the exterior of a residence, substantially as herein shown and described.

WILLIAM K. BENEDICT.
